(57) CLAIM

The ornamental design for an electric razor head, as shown and described.

DESCRIPTION

FIG. 1 is a top, front, left side perspective view of an electric razor head showing my new design;

FIG. 2 is a bottom, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate a portion of the electric razor head that forms no part of the claimed design.
